US00D568278S

(12) **United States Design Patent** (10) **Patent No.:** **US D568,278 S**
Kim et al. (45) **Date of Patent:** **** May 6, 2008**

(54) **PORTABLE PHONE**

(75) Inventors: **Jin-Soo Kim**, Yongin-si (KR); **Nam-Mi Kim**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/258,216**

(22) Filed: **Apr. 19, 2006**

(30) **Foreign Application Priority Data**

Oct. 28, 2005 (KR) 30-2005-0036459

(51) **LOC (8) Cl.** **14-03**

(52) **U.S. Cl.** **D14/138**

(58) **Field of Classification Search** D14/496, D14/138, 341-347; 455/575.3, 575.1; D21/517, D21/329, 333

See application file for complete search history.
